UNITED STATES PATENT OFFICE.

WILLIAM WOLFE, OF OAKBROOK, PENNSYLVANIA, ASSIGNOR TO THE NOLDE & HORST CO., OF READING, PENNSYLVANIA, A CORPORATION OF PENNSYLVANIA.

FOLDED-BLANK BOX.

1,110,853.

Specification of Letters Patent. Patented Sept. 15, 1914.

Application filed March 6, 1913. Serial No. 752,272.

To all whom it may concern:

Be it known that I, WILLIAM WOLFE, a citizen of the United States, residing at Oakbrook, in the county of Berks and State 5 of Pennsylvania, have invented certain new and useful Improvements in Folded-Blank Boxes, of which the following is a specification.

My invention consists in the improved folding box blank, and the composite box structure of which it forms a part, as hereinafter fully described in connection with the accompanying drawings and specifically pointed out in the claims; the main object 15 of the invention being to provide an improved box structure the goods-receiving space of which is irregularly shaped by means of suitable wall-extensions of the folding blank, and the folded form of said blank being retained by separably-fitted box parts.

The construction particularly illustrated in the drawings as embodying my invention, is especially adapted for containing hosiery 25 in the form to which it is most conveniently folded for boxing, the blank being folded to the required form and its shape retained without pasting.

Figure 1 is a perspective view showing 30 the complete box blank with one end wall, and one side wall and its platform extension, completely folded; the flat position of said end wall portion of the blank being also indicated, in dotted lines; and the scored 35 folding-lines of the flattened portions of the blank being represented by dots. Fig. 2 is a separate view of the false-bottom key-piece which is inserted in the complete folded-up box to lock the same. Fig. 3 is a plan view 40 of the folded-up box with the key-piece in place. Fig. 4 is an end elevation, a portion of the end wall being broken away on the line 4-4 of Fig. 3. Fig. 5 is a cross-sectional view on the line 5-5 of Fig. 3. Fig. 45 6 is a longitudinal section on the line 6-6 of Fig. 3. Fig. 7 is a perspective view of a modified form of box embodying my invention, the shape of the flattened blank being indicated in dotted lines. Fig. 8 is a partial 50 plan view showing a slightly modified form of end-wall platform and indicating in dotted lines the corresponding form of the flattened blank. Figs. 9 and 10 are similar views to Figs. 1 and 3, showing a modification 55 of my invention which is adapted for

use as a box insert, the inclosing box being indicated in dotted lines in Fig. 10.

My complete invention provides for interlocking folded-up side and end walls carrying folded-up extensions forming hollow platforms of determined shape and location within the box; the single blank employed comprising a bottom portion 2, side wall portions 3, 3, and end wall portions 5 and 6.

In the preferred complete-box construction indicated in Figs. 1 to 8 inclusive, each side wall portion 3 is provided with an in-turned locking end 10, and also with a platform extension for a part of its length adjacent the end wall portion 5; said extension 65 consisting of a top section 12, a vertical wall section 13, and a bottom section 14, which sections are adapted to fold on the scored lines 15, 16, 17 so as to form a hollow rectangular platform with the horizontal-top 70 section 12 in the plane of the top edges of the box, and the parallel section 14 resting upon the bottom 2 and spacing the vertical section 13 from the side wall 3 of the box. As shown this hollow rectangular platform 75 is closed diagonally at its exposed inner end, approximately midway of the length of the box, by a folding vertical wall section 18 of the blank, having a bottom-contacting extension 19, and by interlocking inturned ends 80 85 20 and 21 of the sections 18 and 14; while its outer end is closed by the end wall 5, preferably with one or more end closure extensions 22, 23, 24 of said sections folded in so as to give rigidity to the structure.

The end wall 5 of the box, which closes against the adjacent ends of the rectangular platforms, is provided with locking ends 25, 25 which are turned into the latter, and retained by one or all of said end closure extensions 22, 23, 24; and it is also provided, 90 as shown, with a spacing-flap extension 26, 27, which is folded against the inner face of the wall 6, between the two side wall platforms, with the end portion 27 thereof resting upon the bottom of the box. The opposite end wall 6 is provided with a triangular extension 30, which is adapted to fold on the scored line 31 over the inturned locking ends 10 of the side walls 3, 3, so as to 100 105 form the top of a triangular platform having its point extending centrally into the box; the vertical walls of said platform being formed by connected sections 32, adapted to fold on the scored lines 33, and the 110

end portion 34 of said sections 32 being folded on the scored lines 35 so as to rest upon the bottom of the box. One of said sections 32 is also provided with an in-folding locking end 36, which gives added rigidity to the folded-up platform.

When the side wall and end wall portions of the blank, with their extensions, have been folded up in interlocked form as described and shown, the box with its inwardly extending platforms is completely formed, and it is only necessary to provide for retaining such form for service. This I accomplish in a simple manner, and without pasting or otherwise permanently fixing the folds, by means of a false-bottom key-piece 40, which is accurately cut to the interior outline of the platform box, and is pressed firmly down into the latter upon the bottom-contacting portions 19, 27, 34 of the wall extension sections, so as to firmly hold the folded form and at the same time neatly complete the interior finish of the box.

The preferred shape and arrangement of the platforms as specifically described, may be readily modified without departing from the main features of my invention, as indicated in Figs. 7 and 8; Fig. 7 showing only one of the side walls of the box provided with an inwardly extended platform, and the triangular end-wall platform being correspondingly changed in form; and Fig. 8 indicating another slight modification of said triangular end wall platform, the purpose of which is to reduce the interior size of the box while maintaining a determined standard size exteriorly.

The embodiment of my invention as above described provides for the construction of a complete box from a single blank; which box may either be used alone, if made of suitably strong material, or may be used merely as a liner insert in a separate box of any desired construction, in which case it may be formed of lighter material especially adapted for interior finish only. In the modification shown in Figs. 9 and 10, which is adapted only for use as a lining insert in a separate box indicated by the dotted lines 50 of Fig. 10, the main portions of the side walls 3, 3' of the specifically described construction (Figs. 1 to 8) are dispensed with, and the false-bottom key-piece 40 may also be omitted, as the snugly fitted inclosing box 50 will serve to sufficiently retain the folded form of the blank.

In the Figs. 1 to 8 construction, it will be readily seen that the flaps 26 produce a rounded edge on the box end 5 instead of showing a cut edge as on the sides 3-3', and

that similar flaps might be employed on the sides to produce a similar edge finish.

What I claim is:—

1. A rectangular box made up of a folded blank comprising a bottom portion and a wall portion having a folding inverted-box extension forming a hollow platform upon said bottom portion; and an insertible false-bottom piece for supporting the folded blank.

2. A rectangular box made up of a folded blank comprising a bottom portion and a wall portion having a folding inverted-box extension forming a hollow platform, with projecting tabs, upon said bottom portion; and an insertible false-bottom piece for supporting the folded blank.

3. A folded-blank rectangular box comprising bottom, end-wall, and side-wall portions, one of said end-wall portions having an inverted-triangular-box extension forming a hollow platform in the main box, and one of said side-wall portions having a rectangular box extension forming a folded hollow platform in the main box for a portion of its length; and an inserted false-bottom key-piece.

4. A folded-blank rectangular box comprising bottom, end wall and side wall portions, one of said side-wall portions having a folding rectangular-box extension forming a hollow platform in the main box extending part way of its length and provided with a diagonally-closed end intermediate of the end walls of the main box, and a separately fitted support for said extension substantially conforming in shape to the folded-blank rectangular box.

5. A tray like receptacle made up of sheet material in two separately formed parts, one of said parts comprising a bottom portion and a wall portion having a folding inverted box like extension forming a hollow platform upon said bottom portion, the other of said parts being separately fitted to and retaining the first said part in its folded form.

6. A tray like receptacle made up of a blank comprising a bottom portion having a folding inverted box extension forming a hollow platform upon said bottom portion, and a separately fitted fold retaining support for the box extension and engaging with a side wall portion of said box extension.

In testimony whereof I affix my signature in presence of two witnesses.

WILLIAM WOLFE.
